[57] **CLAIM**

The ornamental design for the folding router table, as shown and described.

DESCRIPTION

FIG. 1 is a perspective view of the router table of the present invention.

FIG. 2 is a top view of the router table of the present invention.

FIG. 3 is a first-end view of the router table of the present invention.

FIG. 4 is a side view of the router table of the present invention the opposite side being a mirror image thereof.

FIG. 5 is the opposite end view opposite that illustrated in FIG. 3 of the router table of the present invention.

FIG. 6 is a side view of the router table in the folded position; and,

FIG. 7 is a top view of an alternative embodiment of the router table of the present invention.
